UNITED STATES PATENT OFFICE

109,391

DESIGN FOR A FINGER RING

Julius H. Coleman, Baltimore, Md.

Application February 16, 1938, Serial No. 75,161

Term of patent 14 years

To all whom it may concern:

Be it known that I, Julius H. Coleman, a citizen of the Republic of Lithuania, residing at Baltimore, State of Maryland, have invented a new, original, and ornamental Design for Finger Rings, of which the following is a specification, reference being had to the accompanying drawing, forming part thereof.

Figure 1 is a plan view of a finger ring, showing my new design.

Figure 2 is a side elevation thereof.

Figure 3 is a side elevation of a finger ring showing the top or lid in its open position.

Figure 4 is an edge view of the ring.

I claim:

The ornamental design for a finger ring, as shown.

JULIUS H. COLEMAN.
